(57) **CLAIM**

The ornamental design for a conveyor yoke, as shown and described.

DESCRIPTION

FIG. 1 is a perspective view of a conveyor yoke according to our new design;

FIG. 2 is a front elevational view of the conveyor yoke shown in FIG. 1, a rear elevational view being a mirror image of the front elevational view;

FIG. 3 is a left side elevational view of the conveyor yoke shown in FIG. 1, the right side elevational view being a mirror image of the left side elevational view;

FIG. 4 is a top plan view of the conveyor yoke shown in FIG. 1, a bottom plan view not being shown as it is devoid of ornamentation;

FIG. 5 is a perspective view of a second embodiment of the conveyor yoke;

FIG. 6 is a front elevational view of the conveyor yoke shown in FIG. 5, a rear elevational view being a mirror image of the front elevational view;

FIG. 7 is a left side elevational view of the conveyor yoke shown in FIG. 5, a right side elevational view being a mirror image of the left side elevational view; and,

FIG. 8 is a top plan view of the conveyor yoke shown in FIG. 5, a bottom plan view not being shown as it is devoid of ornamentation.

The broken lines in FIGS. 1-8 are for illustrative purposes only and form no part of the claimed design.
